UNITED STATES PATENT OFFICE.

JAMES McDONOUGH, OF MONTCLAIR, NEW JERSEY.

HEEL-SPREADER FOR HORSES.

SPECIFICATION forming part of Letters Patent No. 645,511, dated March 13, 1900.

Application filed June 12, 1899. Serial No. 720,151. (No model.)

To all whom it may concern:

Be it known that I, JAMES McDONOUGH, a citizen of the United States, residing at Montclair, in the county of Essex and State of New Jersey, have invented certain new and useful Improvements in Heel-Spreaders for Horses; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object the spreading of but one heel of a horse at a time, and particularly the heel which extends abnormally inward toward the center of the foot. Heretofore heel-spreaders have, so far as I am aware, pressed oppositely with equal force against both heels of the animal's foot, and thus, while tending to cure the abnormal formation, have at the same time pressed out the normal side of the foot, so that the heels remained at unequal distances from the center, it being understood that when the heels are at equal distances from the center they equally support the weight of the animal; but by pressing out one heel from the center of the foot the pressure of such heel on the ground diminishes and the one nearer the center is caused to carry an overamount of weight. Thus an abnormally-inturned heel, with its undue pressure, tends to produce corns, water-cracks, or the like upon the foot, or otherwise tends to the discomfort and lameness of the animal.

The invention consists in the improved heel-spreader and in the arrangement and combinations of parts of the same, all substantially as will be hereinafter set forth, and finally embraced in the clauses of the claim.

In the present construction I have provided means by which the spreading force is directed only upon that heel of the horse which is abnormally contracted or inwardly extended.

With these objects in view I have provided the construction shown in the drawings, in which like letters of reference indicate corresponding parts in each of the several figures.

Figure 1 is a plan of the under side of a

horse's foot, a portion of the pad or plate being broken away. Fig. 2 is a plan of said plate with a spreading-spring attached, held under tension by a key. Fig. 3 is a detail view of said key, and Fig. 4 is a detail view of the spreading-spring.

In said drawings, *a* indicates the horse's foot, and *b* the pad or plate, preferably of leather, adapted to be interposed between the bottom of the horse's foot and the shoe and be held in place by said shoe and the nails which fasten said shoe to the hoof. The said plate in plan is shaped to conform more or less closely in outline to the foot and on the upper side receives the spreading-spring *c*. This comprises a single pronged piece of heavy resilient wire turned at one end to form an oblong eye *d*, by means of which it is fastened non-pivotaly upon the leather pad or plate *b*. I prefer to employ a pair of rivets *e e* in fastening said spring to the plate *b*, said rivets being inserted through the plate and arranged at opposite ends of the slot *d'*, formed in said eye, to prevent turning. At its opposite end the single prong of said spring is provided with a laterally-bent tooth *f*, adapted to enter the heel of the foot. The spring is so fastened upon the plate *b* as that it will require flexing preliminary to the application of the plate to the foot and so that when said plate is so applied said spring will bear against the abnormal heel to press the same outward or away from the center of the foot.

To hold the spring in a flexed position while the plate is being applied to the foot, I have provided a key *g*, consisting of a bent piece of wire, the bit *g'* of which is adapted to enter one of a series of holes *h h h* found in the plate near the heel and catch upon the tooth *f*, so as to hold the free end of the spreading-spring away from the heel during the operations of applying the plate and shoe *i* to the foot. After such applying operations the key may be withdrawn, when the spring is free to press outward against the heel.

Having thus described the invention, what I claim as new is—

1. The improved heel-spreader for horses, comprising a supporting-plate and a single independent resilient prong to press against the abnormal heel, substantially as set forth.

2. The improved heel-spreader for horses, comprising a leather plate adapted to be interposed and held between the horse's shoe and foot and an independent spreading-spring fastened to said plate at one end and having a tooth at its opposite free end, substantially as set forth. 5
3. The improved heel-spreader for horses, comprising a supporting-plate and conforming in general outline to the foot of the animal, and a spring fastened to the fore part of said plate and extending back toward the heel portion thereof, where it is free to engage the heel of the animal, substantially as set forth. 10
4. The improved heel-spreader, comprising a plate, a spring slotted at one end and having a lateral tooth at the opposite free end, 15

and rivets for holding said spring to said plate, substantially as set forth. 20

5. The improved heel-spreader, comprising a plate having a series of holes, a spring slotted at one end and having a tooth at the other, fastening means and a key, all arranged and adapted to operate, substantially as set forth. 25

6. The improved heel-spreader, comprising a spreading-spring, and a lock for holding said spring out of spreading relation to the heel, substantially as set forth. 25

In testimony that I claim the foregoing I have hereunto set my hand this 7th day of June, 1899.

JAMES McDONOUGH.
